H. FRANZKY & J. WIECZOREK,
DEVICE FOR HOLDING REINS, LEASHES, AND THE LIKE,
APPLICATION FILED APR. 10, 1911.

1,034,779.

Patented Aug. 6, 1912.

UNITED STATES PATENT OFFICE.

HUGO FRANZKY, OF LIEGNITZ, AND JOSEPH WIECZOREK, OF HAYNAU, GERMANY.

DEVICE FOR HOLDING REINS, LEASHES, AND THE LIKE.

1,034,779.

Specification of Letters Patent.

Patented Aug. 6, 1912.

Application filed April 10, 1911. Serial No. 620,240.

To all whom it may concern:

Be it known that we, HUGO FRANZKY and JOSEPH WIECZOREK, subjects of the German Emperor, and residents of 2 Bolkostrasse, 5 Liegnitz, Silesia, Germany, and 27 Bahnhofstrasse, Haynau, Silesia, Germany, respectively, have invented certain new and useful Improvements in Devices for Holding Reins, Leashes, and the Like, of which the 10 following is a specification.

The present invention relates to a holder for the reins or leashes of teams left alone and the like. It is a known fact, that the running away of teams left alone may frequently have been avoided if a safe means of securing the reins or leashes had been at disposal.

The present invention has the object to provide such means.

20 The arrangement consists essentially in a clamping device fitted to the carriage or the like in a detachable manner, which device can be operated by means of a hand lever. The latter is preferably fitted to an elastic 25 plate which will clasp the reins or leashes. The operating lever for the clamping device is preferably elastically journaled, so as to allow of a convenient manipulation. The provision is preferably made that the clamping 30 device may be secured to one or the other side of the carriage as the case may require.

In the accompanying drawing the present invention is exemplified in a constructional form.

35 Figure 1 is a side elevation of the device opened; Fig. 2 is a side elevation of the device while in use; Fig. 3 shows the device fitted to a carriage.

To the side 1 of the carriage or at any 40 other suitable part a plate 2 is secured by means of screws or the like. This plate is provided with one or several eyes 3, in which the clamping device proper is fixed. The latter consists in the constructional form 45 shown of a U-shaped strap 4, the one leg of which has a number of hooks 5 corresponding to the said eyes 3, into which said hooks 5 are hung. On the inside of the same leg of the strap 4 and at a suitable distance 50 therefrom is arranged an elastic plate 6. Between this plate and the respective leg of the strap 4 the reins or leashes 2 are passed and held securely in their position by the elastic plate 6 being clamped against 55 them. For increasing the safety, the surfaces of the plate 6 and the leg of the strap

between which the reins are clamped may be provided with corrugations, points and the like.

For pressing the plate 6 against the leg 60 of the strap 4 a hand lever is provided, which is pivoted on a pin 7 to the second leg of the strap 4. This lever is double armed and its outer end 8 serves as a handle, while the second arm 9 acts on the elastic plate 6. 65 By pressing down the hand lever 8 the leash 2 is securely clasped. In consequence of its shape the lever 8, 9 is secured in its position against being unintendedly moved (Fig. 2). For facilitating the opening of 70 lever 8, 9 and for avoiding too great a strain on the pin 7, the ears 10 carrying the same are elastically secured to the leg of the strap. These ears penetrate for this purpose the leg of the strap with a pin 11, on the 75 end of which a spring 12 is arranged. The said spring 11 is secured by means of a nut or plate 13.

For preventing the clamping device from jumping out of the eyes 3 while the carriage is moving, one or several of the hooks 5 are provided with a clasping spring 14 of suitable shape.

The plate 2 with the eyes 3 is preferably provided on both sides of the carriage, so 85 that the clamping device may be attached at will on either side.

The device according to the present invention may also be made of a smaller size and be attached to the saddle of a riding 90 horse for holding the reins of the latter. The rider will then have both hands free for other purposes, such as reading a card, writing or the like and yet have the reins ready at hand at any moment. 95

We claim:

1. A rein-holder comprising in combination a U-shaped strap, adapted to be detachably fixed to a wall of a carriage, etc., an elastic plate arranged inside of said strap 100 and having its one end fixed to one leg of said strap, a bearing movably connected to the other leg of said strap, springs for holding said bearing in position, and a two-armed lever journaled in said bearing and 105 having its one arm acting on said elastic plate, substantially as set forth.

2. A rein-holder comprising in combination a U-shaped strap, hooks secured to said strap and adapted to be engaged into eyes 110 fixed to a wall of a carriage, etc., a clasping spring on said hooks adapted to secure the

latter in said eyes, an elastic plate arranged inside of said strap and having its one end fixed to one leg of said strap, a bearing movably connected to the other leg of said strap, springs for holding said bearing in position, and a two-armed lever journaled in said bearing and having its one arm acting on said elastic plate, substantially as set forth.

In testimony whereof we have hereunto

signed our names this 17th day of March 10
1911, in the presence of two subscribing wit-
nesses.

HUGO FRANZKY.
JOSEPH WIECZOREK.
